CLAIM

The ornamental design for a wire mesh crate for burning leaves, as shown and described.

DESCRIPTION

FIG. 1 is a perspective view of a wire mesh crate for burning leaves showing my new design;

FIG. 2 is a front view thereof;

FIG. 3 is a back view thereof;

FIG. 4 is a side view, the opposite side view being a mirror image thereof; and,

FIG. 5 is a top view, bottom view is mirror image thereof. In FIG. 1, the broken lines showing of environmental structure for purposes of illustrating the wire mesh crate for burning leaves in a condition of use. The broken lines and the structure they depict form no part of the claimed design.
